(57) **CLAIM**

I claim the ornamental design for a welder frame, as shown and described.

DESCRIPTION

FIG. 1 is a top perspective view of an engine welder frame of the new design;

FIG. 2 is a rear view of the engine welder frame of FIG. 1; FIG. 3 is a top elevation view of the engine welder frame of FIG. 1;

FIG. 4 is a bottom view of the engine welder frame of FIG. 1; FIG. 5 is a front view of the engine welder frame of FIG. 1; FIG. 6 is a right side view of the engine welder frame of FIG. 1; and,

FIG. 7 is a left side view of the engine welder frame of FIG. 1.

The portions of the Figures shown in phantom lines form no part of the claimed design and are for illustrative purposes only.

1 Claim, 4 Drawing Sheets
